UNITED STATES PATENT OFFICE.

CLIFTON REEVES, OF TRENTON, NEW JERSEY, ASSIGNOR OF ONE-HALF TO WILLIAM P. CUBBERLEY, OF ROBBINSVILLE, NEW JERSEY.

ENGINE-GOVERNOR.

1,103,077.

Specification of Letters Patent.

Patented July 14, 1914.

Application filed March 22, 1913. Serial No. 756,117.

To all whom it may concern:

Be it known that I, CLIFTON REEVES, of Trenton, in the county of Mercer, and in the State of New Jersey, have invented a certain new and useful Improvement in Engine-Governors, and do hereby declare that the following is a full, clear, and exact description thereof.

My invention relates particularly to the class of engine governors which are known as shaft governors.

The object of my invention is to provide a governor for engines which is balanced on opposite sides of the shaft without the necessity of providing a number of different balancing weights as was hitherto found necessary in previous types of governors of this character, the balancing in a simple manner tending to avoid the undue strain which is put upon governors that are unbalanced or imperfectly balanced, especially in starting and stopping the engine.

The object of my invention is, furthermore, to provide a governor of the above kind in which the unreliability of the coil spring which has hitherto been a serious objection to governors of this character, owing to the change in pressure of the spring, is done away with, thereby avoiding the constant need of regulation and attention of an expert machinist to keep the governor in proper adjustment.

One object of my invention is thus to provide a governor of the above character which shall maintain its adjustment, and which may be easily regulated at all times to accommodate the governor to the speed desired.

Still a further object of my invention is to provide a construction of the kind indicated, which is economical in construction, and which has few parts, thus avoiding the necessity of elaborate repairs.

Another object of my invention is to provide a governor of this kind in which the parts may be readily applied to standard governor wheels and, in fact, other types of governors quite different in construction.

While my invention is capable of embodiment in many different forms, by way of illustration I have shown one form of my invention in the accompanying drawings, in which—

Figure 1 is a side elevation of a governor made in accordance with my invention; and,

Fig. 2 is a vertical cross-section of the same, taken through the center of the governor.

In the drawings I have shown an engine shaft 1 having a governor wheel 2 thereon. Attached to the governor wheel 2, there is an arm 3 pivoted upon a shaft 4 located at one side of the governor wheel 2, and near the shaft 1. One end of the arm 3 carries a plurality of removable balancing weights 5, while the other end of the arm 1 has a slot 6 to receive an adjusting screw 7 having a locking bolt 8 in said slot. Upon the screw 7 in said slot there is provided a sliding carriage 9 which has a pivot 10 upon one end thereof. Upon the other side of the sliding carriage 9 there is a screw threaded bolt 11 carrying a nut 12. The pivot 10 receives one end of an arm 13, the other end of said arm being screw threaded to a weight 14. Within the weight 14 there is a slot or cavity 15 in which there is located a pin 16 for attachment to the end of a leaf spring 17. The other end of the leaf spring 17 is fixedly attached to a bracket 18 upon a portion of the governor wheel 2, while intermediate its ends the leaf spring 17 has a pair of screws 19 having adjusting nuts 19^a located over a connecting plate 19^b, one end of each of which is attached to a similar bracket 20 upon the body of the wheel 2. The parts thus described are arranged so that the centrifugal force due to the rotation of the wheel will cause the weight 14 to move outwardly away from the axis of rotation. In order to control the movement of the weight 14 outwardly and to make said movement gradual and uniform, there is attached to the arm 3 a piston 21, said piston 21 being attached thereto by an arm 22, which arm 22 is adjustably carried in the end of a bracket 23 pivoted upon the arm 3. The piston 21 is supported within a dash pot 24 pivoted to a bracket 25 secured to the inner face of the governor wheel 2. In order to provide a limit to the movement of the weight 14 and the arm 3, I also provide a stop 26 attached to the inner face of the wheel 2, said stop having a fiber plug 27 which contacts with one end of the arm 3. The arm 3 has an elongated opening 28 at its center to permit the passage of the shaft 1 through the same. Upon the arm 3, around the opening 28, I have located an eccentric 29, and around the eccentric there is situated a sleeve 30 made in

105 110

two halves, and attached together by means of bolts 31. One of the halves 30 of the sleeve is attached to a valve operating rod 32 in the usual manner. At one side of the 5 rod 32 the half of the sleeve 30 carries a lubricating box 33 which is adapted to provide lubricating oil to the eccentric. In the operation of the governor, assuming that the parts are in the position of rest, 10 which is the position shown in Fig. 1, the rotation of the shaft 1 will cause the weight 14 to move outwardly, owing to the centrifugal force and in opposition to the force of the spring 17. The outward movement of 15 the weight 14 will cause the arm 3 to be moved in a direction toward the center of the shaft 1, thereby decreasing the extent of movement of the eccentric 29 from one side to the other of the shaft 1. The re- 20 duction of the length of movement of the eccentric 29 will reduce the extent of movement of the valves controlled by the valve rod 32, thereby decreasing the amount of steam admitted to the engine in the case 25 where the governor controls the movement of a steam engine. The amount of steam will be thus reduced in this manner until the speed of the engine is lowered sufficiently to stop the further outward move- 30 ment of the weight 14. The movement of the weight 14 toward and from the center of the shaft 1 is rendered uniform by the presence of the dash pot 24 which cooperates with the arm 3. The presence of the 35 dash pot 24 will also prevent sudden movements of the weight 14, owing to the inertia of the valve gear, thereby avoiding a breakage or disarrangement which might occur in this manner. Any sudden shock to the gov- 40 ernor by reason of the stopping of the engine is prevented by the buffer made of fiber or other similar material 27. The adjustment of the governor may be readily effected by adjustment of the nuts 19^a, the ad- 45 justment of the screw 7 to move the sliding carriage 9 toward or away from the center of the shaft 1, or by changing the weights 5 which are carried upon the other end of the arm 3. By this means a very perfect ad- 50 justment of the governor may be obtained, which adjustment remains permanent. The eccentric 29 is also oiled by the oil from the oil cup 33.

While I have described my invention

above in detail, I wish it to be understood 55 that many changes may be made therein without departing from the spirit of my invention.

I claim:

1. A governor comprising a shaft, a valve 60 controlling arm connected thereto, a band spring, a weight thereon, a link connecting the weight to the arm, and a screw located on the arm to adjust the position of the link connection therewith. 65

2. A governor comprising a shaft, a valve controlling arm connected thereto, a band spring, a weight thereon, a link connecting the weight to the arm, and a screw located longitudinally on the arm to adjust the position of the link connection therewith. 70

3. A governor comprising a shaft, a valve controlling arm connected thereto, a band spring, a weight thereon, a link connecting the weight to the arm, and a screw located 75 longitudinally in a slot on the arm to adjust the position of the link connection therewith.

4. A governor comprising a shaft, a weighted valve controlling arm connected 80 thereto, having means for attaching additional weights thereto, a band spring, a weight thereon, a link connecting the weight to the arm, and a screw located on the arm to adjust the position of the link connection therewith. 85

5. A governor comprising a shaft, a weighted valve controlling arm connected thereto, having means for attaching additional weights thereto, a band spring, a 90 weight thereon, a link connecting the weight to the arm, and a screw located longitudinally on the arm to adjust the position of the link connection therewith. 95

6. A governor comprising a shaft, a weighted valve controlling arm connected thereto, having means for attaching additional weights thereto, a band spring, a weight thereon, a link connecting the weight to the arm, and a screw located longitudinally in a slot on the arm to adjust the position of the link connection therewith. 100

In testimony that I claim the foregoing I have hereunto set my hand.

CLIFTON REEVES.
